UNITED STATES PATENT OFFICE

FREDERICK W. ROETTGES, OF NEW YORK, N. Y., AND JULIUS T. GUTZWA, OF MERIDEN, CONNECTICUT, ASSIGNORS TO LIGHTING APPLIANCE COMPANY, INC., OF NEW YORK, N. Y.

DESIGN FOR A BASE PLATE FOR A LIGHTING FIXTURE OR ARTICLE OF SIMILAR NATURE

Application filed May 28, 1930. Serial No. 35,830. Term of patent 3½ years.

To all whom it may concern:

Be it known that we, FREDERICK W. ROETTGES, a citizen of Germany, residing in New York, in the county of Kings and State of New York, and JULIUS T. GUTZWA, a citizen of the United States, residing in Meriden, in the county of New Haven and State of Connecticut, have invented a new, original, and ornamental Design for a Base Plate for a Lighting Fixture or Article of Similar Nature, of which the following is a specification, reference being had to the accompanying drawing, forming a part thereof.

Figure 1 is a front elevational view of a base plate for lighting fixture, showing our

new design, in which the parts shown in plain outline involve mere repeats of the portions shown completed in full lines.

Fig. 2 is a bottom plan view thereof, in which the parts shown in plain outline involve mere repeats of the portions shown completed in full lines.

We claim:

The ornamental design for a base plate for a lighting fixture or article of similar nature, as shown and described.

In testimony whereof, we affix our signatures.

FREDERICK W. ROETTGES.
JULIUS T. GUTZWA.
